INCANDESCENT FILAMENT LAMP

Doris E. Straty and Stephen Straty,
Milwaukee, Wis.

Application April 28, 1934, Serial No. 722,992

6 Claims. (Cl. 176—24)

This invention relates to an improvement in incandescent filament lamps, and more particularly to an electric lamp for use in series relation to other similar lamps, and provided with a shunting device which is thermally responsive to the filament of the lamp with which it is associated.

Lamps to be grouped in series are now, and have been for some time, in common use. Examples of such use are the lighting arrangement generally used for decorative purposes, and for trimming Christmas trees, where it is the usual practice to use filament lamps having no means for establishing a shunt path around the lamp when its filament becomes ruptured or "burned out". Therefore, in the event the filament of any lamp in the circuit becomes broken or inoperative, the circuit is opened, with the result that the remainder of the lamps are extinguished. Many devices have been proposed for overcoming this inherent defect of series lamps, but such devices have met with little, if any, success in the art because of their impractical, expensive and generally complicated construction.

It is, therefore, an object of this invention to so construct an incandescent filament lamp that in case the filament of the same is ruptured or for any reason becomes inoperative, a new path for the electric current is automatically established so as to short-circuit or shunt the defective lamp from the system, leaving the remainder of the lamps in the circuit unaffected.

It is also an object of this invention to provide a lamp construction which will facilitate the detection of a burned-out or inoperative lamp in a series lighting circuit.

A further object of this invention is to provide a simplified and practical shunting device for an incandescent filament lamp, which may be cheaply produced and without material alteration or modification of manufacturing processes or machine methods now employed in the quantity production of incandescent filament lamps.

Other objects and attendant advantages of this invention will be manifest from the detailed description following.

In the attached drawing, which discloses a preferred embodiment of this invention:

Figure 1 is an elevational view of a lamp construction embodying this invention;

Figure 2 is a detail view of the thermostatic device shown in Figure 1; and

Figure 3 is a detail view of a modified thermostatic device.

Referring to the drawing, the lamp of our in-

vention comprises a sealed enclosure or glass bulb 1, having an externally threaded base 2, and glass stem 3, all of conventional construction. Lead-in wires 4 are mounted in the glass stem 3 and at their upper ends support, in any suitable manner, an incandescent light-emitting filament 5. Each lead 4, in addition, carries an arm or thermostatic element 6, which may be formed, for example, of two metal strips 7, 8 having different co-efficients of expansion. The inner strip 7 may be made of metal having a greater co-efficient of expansion than the metal of outer strip 8. The lower ends 9 of the arms 6 are secured to leads 4 in any suitable manner, as by welding. Each arm 6 at its outer end 10 carries a contact member or button 11. These latter contacts are of suitably chosen material having a proper resistance value to insure the passage of sufficient current through the filament to substantially heat the same when current is supplied thereto.

Referring now to the operation of the lamp, Figure 1 shows the position assumed by the arms 6 when the filament is thermally inactive or cold. When the lamp is placed in circuit, and current allowed to flow through the circuit, current flows through both filament 5 and shunt path 6, 11, 11, 6. Filament 5 thus becomes heated and this heat is transmitted to the arms 6. The latter, by the unequal expansion of their component metal strips 7, 8, from which each arm is formed, move oppositely at the outer ends 10 to separate the contacts 11 (see Fig. 2). As long as filament 5 remains unbroken and incandescent or thermally active, arms 6 will remain in a warped position and maintain the contacts 11 in the separated or open-circuit position shown in Fig. 2. In the event filament 5 becomes broken or burned out during the course of use, current ceases to flow through same, and the filament becomes cold or thermally inactive. Immediately the filament becomes cool or thermally inactive, the thermostatic arms 6 will begin to cool. This cooling of arms 6 causes their return to the position shown in Figure 1. Contacts 11 will then abut each other, and a path for current flow through the lamp, by way of the shunt path formed by leads 4, arms 6, and contacts 11 will be established. This shunt path will serve to maintain the lamp circuit closed, and thereby insure a supply of current to the other lights in the circuit. As all of the lights but one are now lit, the lamp with the burned-out or broken filament is readily detected, and may be replaced.

When the filament of a lamp becomes inopera-

tive during its use in a series circuit, only a short interval of time may elapse before the arms 6 cool sufficiently to bring contacts 11 together and close the shunt circuit. During such interval, the 5 circuit will be open and all of the lamps will be extinguished. A signal, therefore, will be given that one of the lights is no longer of use.

A modified construction for the thermostatic device is shown in Figure 3, where only one of the 10 two arms mounted on lead-in wires 4 is constructed as a thermostatic element. This arm 12 is similar in detail to the arms 6 shown in Figures 1 and 2, being formed, for example, of two metal strips 7, 8 having different coefficients of expansion. The other arm 13 is formed in any suitable way so as to serve as a stationary conducting support for the contact element 11 which it carries. Arm 12 which also carries a contact element 11 operates in the same manner as the arms 15 20 6 of Figures 1 and 2. Thus, when filament 5 becomes heated, the heat is transmitted to the thermostatic element 12, and the latter moves away from the stationary arm 13 to effect separation of contact elements 11. When filament 5 cools 25 or burns out, thermostatic element 12 will move toward the stationary arm 13 to close the gap between contact elements 11, and establish a path for current in shunt to the filament.

While only two embodiments of this invention 30 have been shown and described, other forms and modifications embodying the invention may be readily devised within the spirit and scope of the invention, as defined in the following claims.

We claim:

- 35 1. An electric lamp for use in series lighting comprising, a sealed enclosure, a pair of filament supporting leads extending into said enclosure, a filament connecting the ends of said leads, and a thermostatic device for establishing a conducting path across said leads in shunt to said filament when the latter is thermally inactive, said device comprising, an arm mounted on each of said leads and electrically connected thereto, and a pair of electrical contacts supported in abutting position by the free ends of said arms, at least one of said arms being a bi-metallic member responsive to temperature changes in said filament and operative to bring said contacts together whenever said filament is thermally inactive, said contacts having such ohmic resistance that when in the closed position current will flow through said filament sufficient to heat the latter and cause said thermostatic device to assume the open circuit position.
- 40 45 50 55 2. An electric lamp for use in series lighting comprising, a sealed enclosure, a pair of leads extending into said enclosure, a filament connecting the ends of said leads, and a thermostatic shunt device electrically connecting said

leads, said device comprising an arm secured to one of said leads and in electrical contact with the other of said leads, said arm being responsive to temperature changes in said filament to break said electrical contact when said filament is thermally active.

3. An electric lamp for use in series lighting comprising, a sealed enclosure, a pair of leads extending into said enclosure, a filament connecting the ends of said leads, and a thermostatic shunt device electrically connecting said leads, said device comprising a bi-metallic arm secured to one of said leads and in electrical contact with the other of said leads, said arm being responsive to temperature changes in said filament to break said electrical contact when said filament is thermally active and to maintain the said electrical contact when said filament is thermally inactive.

4. An electric lamp for use in series lighting comprising, a sealed enclosure, a pair of filament supporting leads extending into said enclosure, a filament connecting the ends of said leads, an arm mounted on each of said leads and within said enclosure, the free ends of said arms being in electrical contact with each other to establish a shunt path across said leads, at least one of said arms comprising a member responsive to temperature changes in said filament and operative to break said electrical contact when the filament is thermally active.

5. An electric lamp for use in series lighting comprising, a sealed enclosure, a pair of filament supporting leads extending into said enclosure, a filament connecting the ends of said leads, an arm mounted on each of said leads and within said enclosure, the free ends of said arms being in electrical contact with each other to establish a shunt path across said leads, at least one of said arms comprising a bi-metallic member responsive to temperature changes in said filament and operative to maintain said electrical contact when the filament is thermally inactive.

6. An electric lamp for use in series lighting comprising, a sealed enclosure, a pair of filament supporting leads extending into said enclosure, a filament connecting the ends of said leads, an arm mounted on each of said leads and within said enclosure, the free ends of said arms being in electrical contact with each other to establish a shunt path across said leads, each of said arms comprising a movable member responsive to temperature changes in said filament, said arms being operative to maintain said electrical contact when the filament is thermally inactive.
